LAMP-FOCUS-SECURING DEVICE.

Application filed December 12, 1927. Serial No. 289,332.

This invention relates to a device for preventing lamps from getting out of focus after having been properly set. The invention is particularly designed for use on the head-lights of automobiles and in similar places where the lamp is focused by moving it forward and back along the axis of a mirror by means of a screw.

The principal object of the invention is to provide means whereby, when said screw is turned to the proper position, it can be fastened up in a very simple way and will not thereafter be unscrewed by the jars and jolts to which the structure is subjected and also to provide this means in a very simple and inexpensive form and without the addition of expensive parts.

Reference is to be had to the accompanying drawings in which Fig. 1 is a central sectional view of a head-light of an automobile with a preferred embodiment of this invention applied thereto, and

Fig. 2 is a similar view of the central parts on enlarged scale.

As is well understood the lamp socket 10 is held and guided in a cylindrical guide 11 at the rear of a mirror 12 and located along the axis thereof. The lamp 13 mounted in the socket is adapted to be adjusted back and forth along the axis of the mirror to get it into proper focus. This is done by a screw 14 entering a screw-threaded projection 15 on the socket.

Usually this screw has been provided with a head on the outside of the headlight casing 20 and it is turned to the proper position to get the lamp focused and left there. The jolting of the car tends to turn the screw which has the effect of unscrewing it from the projection 15. Ordinarily there is nothing to prevent this and lamps get out of focus very rapidly after having been adjusted.

For the purpose of positively preventing the unscrewing of the screw 14 we provide it with a fixed integral collar 16 which rests against the inner side of the casing 20 and is pressed thereagainst by a spring 17 which bears at the other end on the projection 15.

We also provide the screw 14 with a reduced integral end 18 extending through an opening in the back of the casing 20 and provided with a left handed screw thread.

On the left handed screw thread is placed a nut 19. 55

In the use of the device the screw 14 is turned in the usual way by inserting a screw driver in the slotted end of the screw exposed at the back of the lamp casing. Of course, the collar 16 always remains back against the casing 20 and the spring 17 tends to force the socket 10 as far forward as possible. The lamp having been adjusted to the proper position the nut 19 is put on and turned up firmly against the casing 20 at the rear. 60

It is obvious that the vibrations of the car cannot have any continuous or permanent effect on the adjustment of the parts except by unscrewing the screw 14 in the passage of the projection 15. But when the screw turns in that direction it necessarily tightens up the nut 19 in the left handed screw 18 and stops the unscrewing of the screw 14 when it commences. 75

Therefore the lamp will remain in focus and under ordinary usage will not get out of focus at any time. This constitutes a very simple and inexpensive way of preventing the difficulty herein mentioned, involves no 80 expensive parts and there is nothing that is likely to get out of order in use.

Although we have illustrated and described only one form of the invention we are aware of the fact that modifications can be made therein by any person skilled in the art without departing from the scope of the invention as expressed in the claims.

Therefore, we do not wish to be limited in these respects but what we do claim is:— 90

1. In a headlight, the combination with a lamp casing, a reflector, a lamp socket and a guide therefor, of a screw connected with the socket for moving the socket for adjustment relative to said reflector, a collar integrally mounted on the screw, a spring on the screw exerting opposite forces on the socket and collar to force the collar against the lamp casing, said screw having a left handed screw portion of reduced diameter 95 on its end beyond the collar, projecting through the back of the casing, a nut on the left handed screw portion to prevent the adjusting screw from unscrewing, and means on said screw whereby same may be turned. 100
2. In a light, having a casing and a reflec- 105

tor, the combination with a lamp socket and a guide therefor, of a screw connected with the socket for adjusting same relative to said reflector, a collar on the screw, adapted to abut said casing, said screw having a left handed screw portion projecting through the back of the casing, and a nut on the left handed screw portion to prevent the adjust-

ing screw from unscrewing, and means on said screw whereby same may be turned. ¹⁰

In testimony whereof we have hereunto affixed our signatures.
